UNITED STATES PATENT OFFICE

DANIEL W. MACCALLUM, OF CASEYVILLE, ILLINOIS

BOAT

Application filed January 21, 1931. Serial No. 510,151.

My invention relates to improvements in boats and has among its objects the production of a water-craft which shall be neat and attractive in appearance, simple and sturdy in construction, roomy and comfortable in use, capable of making high speeds during its travel along the water, and which will be reliable, efficient and satisfactory for use wherever found applicable.

10 One of the principal objects of my invention is to provide a boat of the kind described, wherein the passengers will be seated in a superstructure similar to the well known type of enclosed motor-vehicle body, and wherein a 15 plurality of boats will be positioned therebelow for supporting the occupants and mechanism, and in which the riders will have much more room and comfort than they now have in ordinary boats.

20 Another object of my invention is to provide an auto-craft of the kind described, which shall be driven by air propellers, and wherein the power for driving the latter will be taken directly from the power plant of the 25 motor-vehicle.

Another object of my invention is to provide a plurality of boats for supporting the craft upon the water and in which said boats may be manipulated so as to guide or steer the 30 craft from within the motor-vehicle enclosure.

Another object of my invention is to provide a craft of the kind described which shall have planes or wings thereabove which may 35 be adjustably tilted to permit the air to flow thereunder and tend to lift the craft to the top level of the water, so that said craft will rest but lightly upon the water and decrease the water resistance, with the consequent increase of speed of propulsion.

A still further object of my invention is to provide a steering rudder for such craft, and in which said rudder will not engage in the water but will extend thereabove to further 45 increase the efficiency of the craft.

Many other objects and advantages of the construction herein shown and described will be obvious to those skilled in the art to which this invention appertains, from the disclosures herein given.

To this end, my invention consists of the novel construction, arrangement and combination of parts herein shown and described, and more particularly pointed out in the 55 claims.

In the drawing, wherein like reference characters indicate like or corresponding parts throughout,

Figure 1 is a side elevation of my improved 60 craft; and

Figure 2 is a top plan view of the same.

Referring more particularly to the drawing, wherein I have illustrated the preferred embodiment of my invention, 1 indicates a base or platform of any suitable size, shape 65 and material, the same being supported above the water by a plurality of boats, as for instance by a forward boat 2 and a pair of rear boats 3, the latter being located one at either side of the platform. Struts 4 may be used 70 for connecting the platform to the rear boats, and the forward boat is pivotally connected to said platform, as upon the vertical shaft 5 situated substantially centrally of the boat.

Superimposed upon the platform or base 1 75 is an enclosed cab and power-generating plant, the same being obtained by the use of a motor-vehicle, preferably of the enclosed type, together with the original power plant 80 therein. The motor-vehicle 6 is secured tightly to the platform by any suitable fastening means and is provided with the usual doors 7 through which the passengers may enter or leave.

The power plant of the motor-vehicle is 85 operably connected to one or more air propellers 8 so as to be capable of driving the same, there being two propellers shown in the drawing, one at either side of the front 90 of the platform.

Brackets or standards 9 may be mounted upon the platform, and upon which the propeller shafts 10 are journalled, said propeller shafts being connected through suitable drive 95 connections, as for example belts, gearing, etc., so as to be driven from the power plant of the motor-vehicle.

The forward boat 2 may be steered from the steering wheel 11 of the motor-vehicle 100 through any suitable means, and if desired,

the forward boat may be provided with compartments therein for the storage of oil and fuel, and from which the power-generating plant may be supplied as needed. The rear boats 3 may be used for storage of any sort, as for example of articles of clothing.

A vertical, air engaging vane 13 may be fixedly carried by the forward boat so as to make the latter somewhat easier to steer, and a rudder 14 may be secured upon a vertical axis to the rear of the platform, the latter having tiller or control lines 15 extending therefrom to a point within the cab so as to make the same convenient for steering control.

The keels of the boats are preferably so fashioned that their prow ends are elevated slightly above their rear or stern ends, as for example to about five degrees, to thereby tend to pull the craft to the surface of the water, prevent snagging, and increase the cruising speed of the craft. These boats are preferably shaped so as to have a relatively sharp prow which enables them to cut through the water with minimum resistance.

In order to still further decrease water resistance, I have provided front and rear wings or planes 16 and 17 respectively, said planes extending transversely across the platform and preferably being hinged or pivotally connected to their rear and forward supports or uprights 18 and 19 respectively, and I have provided means whereby said planes may be adjustably tilted so as to vary their angle relative to the horizontal plane. This may be done in any suitable or preferred manner, as for example by permitting the forward uprights to move vertically, their lower ends having a rack thereon which meshes with a gear 20 carried upon a shaft 21, the latter being driven in any suitable manner from the motor-vehicle.

When it is desired to tilt the forward ends of the wings 16 and 17 in either direction, the shaft 21 is rotated correspondingly in the desired direction, and both wings 16 and 17 are adjusted simultaneously. These wings serve to catch the wind thereunder and as the craft travels at a relatively high speed along the surface of the water, said planes will tend to lift the craft to the top level of the water and make but light contact therewith, to thereby increase the effective speed of the craft along the water.

It may be mentioned at this point that the wings described are not intended to lift the entire craft bodily above the surface of the water as with hydro-planes, but are for the purpose of reducing the water resistance and to steady the craft in its movement through the water.

Having thus described my invention, it is obvious that various immaterial modifications may be made in the same without departing from the spirit of my invention;

hence I do not wish to be understood as limiting myself to the exact construction, form, arrangement and combination of parts herein shown or described except as necessitated by the prior art and the claims hereto appended. 70

Having fully described my invention, what I claim is:

1. A water-craft comprising a base; a plurality of supporting wings mounted thereabove; a motor-vehicle superimposed upon said base and having a power plant therein; an air propeller at the forward end of the base and driven by said power plant for propelling said craft; means for adjustably tilting said wings; boats mounted below said base for supporting the structure thereabove upon the water; means driven by said power plant to adjustably control the simultaneous tilting of said wings; and means for steering said craft from within the motor-vehicle. 80

2. A water-craft comprising a platform; a steering rudder therebehind and always entirely above said water; wings connected to the forward and rear ends of said platform; a motor-vehicle upon said platform and having a power-generating plant therein; air propellers at the forward end of said platform and driven by said power-generating plant to propel said craft; means operable by said power plant from within said motor-vehicle for adjustably tilting said wings to vary the lift thereof; a pair of boats depending from said platform to either side of the rear thereof; another boat pivotally connected to the forward end of said platform therebelow, and means for steering said last-mentioned boat from within said motor-vehicle. 100

3. A water-craft comprising a base; a plurality of wings mounted thereabove; a motor-vehicle superimposed upon said base and having a power plant therein; air propellers at the forward end of the base and driven by said power plant for propelling said craft; means for adjustably tilting said wings; boats mounted below said base to support said structure upon the water and prevent the same from capsizing; a steering rudder on said base and out of contact with the water and controlled from within the motor-vehicle; and means independent of said rudder for steering said boats from within the motor-vehicle. 110

In testimony whereof I have affixed my signature.

DANIEL W. MacCALLUM.
